ABSTRACT OF THE DISCLOSURE

A rotary piston internal combustion engine of three-disk construction in which three disks are rotatably supported on the eccentricities of an eccentric shaft mutually displaced by 120°; each of the pistons valves the discharge apertures of inlet and outlet channels while each of the three inlet channels downstream of the throttle valve or each of the three suction spaces between inlet and outlet channels of each disk is connected by way of a line adapted to be closed with the compression chamber of that disk whose eccentric leads the eccentric of the first-mentioned disk by 120°; the orifices of the lines in the compression chambers are located within the area of the major axis.

The present invention relates to a rotary piston internal combustion engine of trochoidal three-disk construction in which three pistons, that control or valve apertures of inlet and outlet channels, are supported on eccentricities of an eccentric shaft arranged mutually displaced by 120°.

It has been found that rotary piston internal combustion engines run very unevenly during idling and smaller partial loads. This uneven or unsteady operation is conditioned by the fact that in the overlap dead-center point exhaust gases reach into the suction space which collect in particular in the forward or leading part of the working chamber and therewith render more difficult the ignition. The exhaust gas volume flowing over into the suction space is particularly of significance if by reason of a closed throttle valve, a considerable vacuum prevails in the suction space, i.e., during idling and smaller partial loads.

It has already been proposed heretofore to supply fresh gases under pressure to the space between inlet and outlet channel whereby an overflow of exhaust gases is to be prevented. This fresh gas is removed from the compression chamber of the same disk. The disadvantage of this arrangement resides in that at the beginning of the overlap, i.e., when the corresponding piston corner valves or has just valved the orifice aperture of the suction channel, no excess pressure prevails as yet in the compression chamber so that at the indicated moment, the overflow of exhaust gases cannot be prevented. Another proposal made heretofore suggests with a multi-disk engine to provide within the housing in proximity to the major axis (cold arc), orifices in the working chambers and to connect the same with each other. It is possible therewith to push fuel-air mixture out of the compression chamber into the leading part of the subsequent or trailing suction chamber, to displace therewith the exhaust gases and therewith to improve the ignition capability of the fuel-air mixture. An overflow of exhaust gases into the compression chamber, however, cannot be prevented with the aid of this arrangement.

The present invention aims at considerably reducing

2

with a three-disk engine, the exhaust gas volume reaching the suction chambers and therewith to improve the operating quietness of the engine during idling and smaller partial loads. For this purpose, the compression chamber of each disk is connected according to the present invention by way of an overflow line with the suction space of that disk whose eccentric trails the eccentric of the first-mentioned disk by 120°. The orifice of the overflow line in the compression chamber lies thereby within the area of the major axis (cold arc), most appropriately about 15° behind the major axis as viewed in the direction of rotation of the piston. On the other side, the overflow line terminates either in the inlet channel downstream of the throttle valve or directly 15 in the trochoid-hollow space between the apertures of the inlet and outlet channel. This arrangement effects that during the period of overlap, fresh gases which are under excess pressure, reach into the suction space, that a higher pressure compared to the outlet channel 20 builds up in the suction space and therewith the overflow of exhaust gases into the suction chamber is prevented. This higher pressure in the suction space is achieved already at the beginning of the period of overlap, i.e., directly after the piston corner leading the suction chamber 25 has swept past the aperture of the inlet channel or of the overflow line because at this moment a corresponding high pressure prevails in the compression chamber of the disk connected by way of the overflow line. It is thus assured that at least in the leading and central 30 portions of the working chambers, no exhaust gases are stored so that at the moment of the ignition, an ignitable mixture is always located in front of the ignition source.

A particularly simple construction of the arrangement according to the present invention can be achieved in 35 that the overflow lines are arranged in their entire length within the housing of the engine, for example, as bores in the casing and intermediate parts.

Since an overflow of fuel-air mixture from disk to 40 disk is to take place only during the operation of the engine at idling or smaller partial loads, it is necessary to provide closure mechanisms which close the overflow lines with larger partial loads and full load. These closure mechanisms are appropriately connected with the 45 throttle valves and are actuated simultaneously with the same.

Accordingly, it is an object of the present invention to provide a multi-disk rotary piston internal combustion engine which avoids by simple means the aforementioned shortcomings and drawbacks encountered in the prior art.

Another object of the present invention resides in a 50 rotary piston internal combustion engine which operates smoothly also at idling speed and smaller partial loads.

A further object of the present invention resides in a 55 rotary piston internal combustion engine in which an overflow of exhaust gases into the working chambers during the suction phase is far-reachingly prevented.

Still a further object of the present invention resides 60 in a rotary piston internal combustion engine of the type described above in which an ignitable mixture is always assured for ignition by the ignition source.

Still another object of the present invention resides 65 in a rotary piston internal combustion engine of the type described above which achieves all of the aforementioned aims and objects, yet is simple in construction and can be readily assembled and manufactured without difficulties.

These and further objects, features and advantages of 70 the present invention will become more obvious from the following description when taken in connection with the accompanying drawing which shows, for purposes

of illustration only, one embodiment in accordance with the present invention, and wherein:

The single figure is a schematic view of an internal combustion engine according to the present invention in which the individual disks, that are in practice disposed one behind the other in the axial direction of the engine, are illustrated adjacent one another for the sake of clarity.

Referring now to the single figure of the drawing, reference numerals 1a, 1b and 1c designate conventional engine casings within which rotate the pistons 3a, 3b and 3c in the direction of arrows 2a, 2b and 2c, respectively. The center points 4a, 4b and 4c of the pistons 3a, 3b and 3c rotate along the arcs 5a, 5b and 5c, respectively. The points 4a, 4b and 4c simultaneously represent the eccentric center points of an eccentric shaft in the illustrated position of the pistons 3a, 3b and 3c while the circles 5a, 5b and 5c represent the paths of rotation thereof. The eccentrics are mutually displaced by 120°, in the illustrated example in such a manner that the ignition sequence is a, c, b. The only schematically indicated ignition sources 6a, 6b and 6c as well as the inlet channels 7a, 7b and 7c with the throttle valves 8a, 8b and 8c and the outlet channels 9a, 9b and 9c are arranged in the casings 1a, 1b and 1c. The engine so far described is known per se and forms no part of the present invention.

Two disks each are connected with each other by overflow lines 10a, 10b and 10c, and more particularly one line each 10a, 10b and 10c leads from the compression chamber 11a, 11b and 11c of a disk to the suction channel 7c, 7a and 7b of that disk whose eccentric trails the eccentric of the first-mentioned disk by 120°. The discharge apertures of the overflow lines 10a, 10b and 10c in the compression chambers 11a, 11b and 11c are disposed about 15° behind the major axis 20a, 20b and 20c, as viewed in the direction of arrows 2a, 2b and 2c, respectively i.e., within the area of the cold arc 21a, 21b and 21c, respectively. In the illustrated position of the pistons, an overflow of fuel-air mixture takes place from the compression chamber 11b by way of the line 10b into the suction channel 7a whereby a penetration of exhaust gases into the suction space is prevented during the overlap. No excess pressure has formed as yet in the compression chamber 11a as well as in the chamber 11c and correspondingly also in the inlet channel 7c and 7b connected therewith. This is not necessary since in the illustrated position of the pistons 3b and 3c, exhaust gases cannot reach into the compression chamber.

The overflow lines 10a, 10b and 10c are adapted to be closed off by closure mechanisms 12a, 12b and 12c of any conventional, known construction in order to be able to prevent an overflow of fuel-air mixture during the operation of the engine at larger partial loads and full load. The closure mechanisms 12a, 12b and 12c are appropriately actuated together with the throttle valves 8a, 8b and 8c from the driver's foot pedal.

While I have shown and described only one embodiment in accordance with the present invention, it is understood that the same is not limited thereto but is

susceptible of numerous changes and modifications as known to a person skilled in the art, and I therefore do not wish to be limited to the details shown and described herein but intend to cover all such changes as are within the scope of those skilled in the art.

5 I claim:

1. A rotary piston internal combustion engine of three-disk construction in which three piston means each valving the apertures of inlet and outlet channels, are rotatably supported on eccentrics of an eccentric shaft which are arranged mutually displaced by 120°, characterized by line means adapted to be closed and operatively connecting the area of a respective suction space of each disk with the compression chamber of that disk whose eccentric leads by 120° the eccentric of the first-mentioned disk, the orifices of the line means being located in a corresponding compression chamber within the area of the major axis thereof.

2. An internal combustion chamber according to claim 10 20, wherein the orifice of the line means are located in the compression chambers within the area of the cold arc.

3. An internal combustion engine according to claim 1, wherein the line means connect a respective compression chamber with the corresponding inlet channel downstream of its throttle valve.

4. A rotary piston internal combustion engine according to claim 1, wherein the line means connect a respective compression chamber with the corresponding suction space between the inlet and outlet channels of the respective disk.

5. An internal combustion engine according to claim 1, wherein the orifice of the line means in the compression chambers are located about 15° behind the major axis as viewed in the direction of rotation of the piston.

35 6. An internal combustion engine according to claim 5, wherein the line means are arranged completely within the housing of the internal combustion engine.

7. An internal combustion engine according to claim 40 6, wherein the line means connect a respective compression chamber with the corresponding inlet channel downstream of its throttle valve.

8. A rotary piston internal combustion engine according to claim 6, wherein the line means connect a respective compression chamber with the corresponding suction space between the inlet and outlet channels of the respective disk.

45 9. An internal combustion engine according to claim 5, wherein the line means are arranged completely within the housing of the internal combustion engine.
